UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

DRIVING MECHANISM FOR SLICING MACHINES

Application filed December 9, 1929, Serial No. 412,658, and in Great Britain December 21, 1928.

This invention relates to slicing machines of the type wherein a carriage for supporting the substance to be sliced is adapted to be reciprocated past a rotatable knife by a force exerted directly upon the carriage, and wherein the knife is adapted to be rotated by means connected to the carriage and adapted to be actuated by the movements of the carriage.

10 In machines of this nature, the carriage is generally provided with a handle which is grasped by the operator who uses the handle as a means for imparting movement to the carriage.

15 One object of the present invention is to provide a flexible connection between the carriage and the knife, said flexible connection being used to rotate the knife as the carriage is reciprocated.

20 A further object of this invention is the provision of a suitable free wheel device connected to the knife and actuated by the flexible connection for imparting movement to the knife.

25 Another object of this invention is the provision of pawl and ratchet mechanism between the gears which drive the knife and the flexible element which is connected to the reciprocating table. The pawl and ratchet mechanism is adapted to impart movement to the gears as the flexible element moves in one direction only, or as the carriage moves in one direction only.

30 A still further object of this invention is the provision of a flexible drive which may be endless or not, as desired.

In the drawings:—

Fig. 1 is an elevational view with certain of the parts broken away, of a device embodying my invention;

Fig. 2 is a plan view of the device shown in Fig. 1;

Fig. 3 is an elevational view of a modification of the device shown in Fig. 1; and

Fig. 4 is a plan view of the device shown in Fig. 3.

In Fig. 1, the slicing machine comprises the base 1 having a carriage 2 adapted to reciprocate thereon, said carriage being supported by the anti-friction rollers 3 fastened

to the carriage. The substance 4, which is to be sliced, is mounted on the feed table 5, of the slicing machine, in the usual manner and is clamped thereon by means of a clamping bar 6 supported on the upright guides 7 and 8. This feed table 5 is given a step by step movement toward the cutting plane of the rotatable knife 9 by means of a suitable feeding mechanism (not shown) so that successive slices are cut from the substance at each complete reciprocation of the carriage past the slicing knife.

The rotatable knife 9 is mounted on a shaft 10 journaled in a suitable bearing formed in the casing 11, the casing being integral with or rigidly connected to the base 1 of the slicing machine. The casing 11 is adapted to enclose the driving mechanisms for the slicing machine. This driving mechanism comprises a driven gear 12 fixed to the shaft 10 and a driving gear 13 supported upon a shaft 14 journaled in the casing 11. A pulley 15 is rotatably mounted on the shaft 14 and is yieldingly urged in a clockwise direction, about the shaft 14 by the spring 16 connected at 17 to the pulley 15 and to the casing 11 at 18, the connections 17 and 18 being any suitable form of pin adapted to extend through loops formed at the opposite ends of the spring 16. A ratchet 19 is also mounted on the shaft 14 and is interposed between the gear 13 and the pulley 15. The ratchet 19 is constrained to move with the pulley 15 and may be made integral therewith or rigidly connected thereto, as may be desired. Pawls 20 pivoted on gear 13 are adapted to engage the teeth of the ratchet 19 and springs 21 are used to rotate the pawls into operative engagement with the teeth.

While I have shown flat springs engaging the pawls, I wish it to be understood that, if desired, I may provide any other suitable type of spring, such as a coil spring arranged around the pivot of each pawl for rotating the pawls into engagement with the ratchet teeth. With the pawls arranged as illustrated in Fig. 1, it will be noted that if a counter-clockwise rotation is imparted to the pulley 15, the gear 13 will also be given a counter-clockwise movement due to the en-

gagement of the pawls with the teeth of the ratchet 19. The gear 13 will impart a clockwise rotation to the gear 12 and, as a result, the knife 9 will be rotated in a clockwise direction since the knife 9 and the gear 12 are both rigidly mounted on the shaft 10. However, it will be noted that in the event that the pulley 15 is rotated in a clockwise direction, the pawls 20 will ride over the teeth on the ratchet 19 so that no motion is imparted to the gears 13 and 12 or to the knife 9.

As previously explained, the pulley 15 is given a clockwise rotation by means of the spring 16. In order to rotate the pulley 15 in a counter-clockwise direction, I provide the pulley 15 with a groove in the periphery thereof and fasten one end of a flexible element 22 to the periphery of the pulley at 23 and train the flexible element 22 over the pulley so that it rests in the groove in the periphery thereof. The free end of the flexible element 22 is trained over the guide pulleys 24, 25 and 26 freely rotatable on pivot pins rigidly connected to the base of the machine, the pulleys 24 and 25 being arranged within the housing 27 secured to or made integral with the base 1 of the slicing machine. The other pulley 26 is arranged beneath the upper surface of the base member 1 as best illustrated in Fig. 2.

The carriage 2 has a rod 28 extending downwardly through a slot 29 in the upper surface of the base 1 of the slicing machine. The flexible element 22 is secured to the lower end of the rod 28 by suitable means such as the nuts 30. The carriage is also provided with suitable brackets 31 carrying a handle 32. The flexible element 22 can be made of any suitable material but is preferable to use a stranded wire or cord, or a band constructed of steel or other suitable material.

The operation of the machine is as follows:—The operator grasps the handle 32 and manually reciprocates the carriage 2 on the base 1. The material 4 is given a step by step movement toward the cutting plane of the knife 9 so that successive slices are cut therefrom. As the carriage moves to the left, as viewed in either Figs. 1 or 2, the flexible element is carried along therewith due to its connection with the rod 28. This movement of the flexible element causes the pulley 15 to rotate in a counter-clockwise direction, thereby imparting a counter-clockwise movement to the gear 13 due to the pawl and ratchet connection previously described. Rotation of the gear 13 rotates the gear 12, and, consequently, the knife 9. As the carriage is moved to the right, however, the tension of the spring 16 rotates the pulley 15 in a clockwise direction and the pawls 20 ride over the teeth on the ratchet 19 and no movement is imparted to the knife 9, due to the rotation of the pulley 15. However, the knife 9 is

free to rotate in a clockwise direction due to the free wheel connection between the pulley 15 and the gear 13. If desired, a fly-wheel may be placed upon the shaft 10, or shaft 14, so that the rotation imparted to the knife during the movement of the carriage to the left, will store up energy in the fly-wheel and cause said fly-wheel to rotate the knife during the time that the carriage is moving to the right. In this manner, the knife is kept moving continuously in one direction, as enough energy may be imparted to the fly-wheel to cause the fly-wheel to rotate the knife 9 until the next movement of the carriage 2 to the left. Thus, it will be seen that with a device constructed as shown in Figs. 1 and 2, a motion is imparted to the slicing knife by simply moving the carriage back and forth past the cutting edge of the knife and there is no necessity for providing a separate driving means for the knife.

In Figs. 3 and 4, I have shown a modification of the device shown in Figs. 1 and 2. In this modification, however, it is not necessary to provide a means separate from the carriage for returning the flexible element to its original position, the flexible element being moved in both directions by its connection with the carriage of the slicing machine. In this modification of the device, the slicing machine comprises the base member 1', carriage 2', anti-friction elements 3', feed table 5', clamping element 6', uprights 7' and 8', all of these parts being constructed in substantially the same manner as the corresponding parts 1, 2, 3, 5, 6, 7 and 8, shown in Figs. 1 and 2. The knife 33 is mounted rigidly upon a suitable shaft 34 journaled in the casing 35 made integral with or rigidly connected to the base member 1'. The shaft 34 also carries a ratchet 36 adapted to be engaged by the pawls 37 spring-pressed into engagement with the ratchet 36 by means of the springs 38 and pivotally mounted on the sprocket 39 which is rotatably mounted on the shaft 34.

A chain 40 is trained over the sprocket 39 and also the sprockets 41, 42 and 43 arranged within a casing formed integral with or connected rigidly, as desired, to the side of the base member 1'. A depending member 44 on the carriage 2' extends downwardly through the slot 45 in the upper surface of the base 1' and this downwardly depending member has a lateral extension 46 having a groove 48 in the end 47 thereof, the chain passing through the groove and being held rigidly therein by any suitable fastening means. The carriage 2' is provided with a handle 49 carried by suitable brackets 50 mounted on one end of the carriage.

The operation of the device shown in Figs. 3 and 4 is as follows:—

The carriage 2' is moved as in Figs. 1 and 2 by the operator who grasps the handle 49 and imparts a reciprocation to the carriage

2' past the cutting edge of the knife 33, the depending member 44 being carried along therewith. Since the chain 40 is rigidly connected to the depending member 44, the same is caused to move first in one direction and then in the other, thereby rotating the sprocket 39 in a clockwise direction, as the carriage moves to the left, and in a counter-clockwise direction, as the carriage moves to the right.

10 As the carriage moves to the left and the sprocket, as a result, moves in a clockwise direction, the shaft 34 will be caused to rotate in a clockwise direction due to the engagement of the pawls 37 with the teeth on the 15 ratchet 36. This causes the knife 33 to rotate in a clockwise direction so as to cut slices from the substance 4 as it is moved past the cutting edge of the knife, the slices being deflected, by means of a slice deflector, not shown, onto 20 the receiving table 51', a similar receiving table 51 being shown in Figs. 1 and 2.

As the carriage is moved to the right, in Figs. 3 and 4, the pawls 37 ride over the teeth of the ratchet 36 so that the counter-clockwise rotation of the sprocket 39 does not impart a movement in a similar direction to the knife 33 and the knife is free to continue its rotation in a clockwise direction, due to its 25 inertia. As stated in connection with the modification shown in Figs. 1 and 2, a fly-wheel may be provided to assist the knife in continuing its clockwise rotation during the time when the driving means for the knife is inoperative. If desired, the knife itself may 30 be made heavy enough to act as a fly-wheel.

I wish to have it understood that while I have shown my invention as applied to a slicing machine in which the carriage reciprocates past the knife, the invention is capable of

35 being used with machines of other types, such as those in which the carriage oscillates past the knife, or those in which the carriage moves continuously in one direction about a pivot. Instead of using a free wheel connection such as that shown in the drawings,

it may be found desirable to use some other type of free wheel connection such as a friction clutch arranged within the hub of either the gear 13 or the sprocket 39. Such friction 40 clutches usually consist of a hub portion and an annular portion rotatably mounted thereon with suitable friction gripping devices interposed between the adjacent surfaces of

45 said hub portion and annular portion, the friction gripping devices being operative only when motion is imparted to the hub in a predetermined direction. Also, if desired, the pulley 15 may be mounted upon the shaft

50 10 and connected to the gear 12 in the same manner as it is shown connected to the gear 13 in the drawings. Of course, in this event, it would be necessary to train the cord 22 about the pulley in the opposite direction so 55 that the motion will be imparted to the knife

in the proper direction as the carriage reciprocates.

Obviously those skilled in the art may make various changes in the details and arrangements of parts without departing from the spirit and scope of the invention as defined by the claims hereto appended, and I therefore do not wish to be restricted to the precise construction herein disclosed.

Having thus fully disclosed an embodiment of my invention, what I claim and desire to secure by Letters Patent of the United States is:—

In a slicing machine, the combination with a table, of a rotating slicing knife, of a rotatable spindle upon which said knife is mounted, a free-wheel mounted on said knife spindle and adapted to rotate said knife when said free-wheel is moved in one direction but inoperative to actuate said knife when said free-wheel is moved in the opposite direction, a continuous endless flexible element for driving said free-wheel, and a rigid member on said table and connected directly to said flexible element to move said flexible element as said table and knife move relative toward and from each other, said flexible element being directly connected to drive said free-wheel and extending around idler elements to change the direction of movement of said flexible element to thereby hold said flexible element out of a position which would interfere with the slices as they are cut by the slicing knife from a substance on said support.

In testimony whereof I have signed my name to this specification on this 21st day of November A. D. 1929.

CORNELIS F. M. VAN BERKEL.
